HANDBAG FRAME COVERING MACHINE

Victor Lindenman, Stroudsburg, Pa.

Application November 22, 1935, Serial No. 51,178

10 Claims.

(Cl. 29—84)

This invention relates to new and useful improvements in a handbag frame covering machine.

The invention has for an object the construction of a machine as mentioned which is adapted to cover the frames of handbags with strips of material. More specifically, it is adapted to cover only those types of frames which are formed of channel shaped material. In these types of frames the machine is capable of folding the edges of the covering strips into the hollow of the channel shapes.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a plan view of a machine constructed according to this invention.

Fig. 2 is an elevational view looking in the direction of the line 2—2 of Fig. 1.

Fig. 3 is a bottom view looking in the direction of the line 3—3 of Fig. 2.

Fig. 4 is a fragmentary elevational view taken on the line 4—4 of Fig. 2.

Fig. 5 is a fragmentary enlarged sectional view taken on the line 5—5 of Fig. 1.

Fig. 6 is a transverse enlarged sectional view taken on the line 6—6 of Fig. 1.

Fig. 7 is a fragmentary view similar to a portion of Fig. 5 but showing the parts in another position.

Fig. 8 is a perspective view of one of the parts shown in Fig. 7.

Fig. 9 is an elevational view looking in the direction of the line 9—9 of Fig. 2.

Fig. 10 is a perspective view of a handbag frame covered with material by the machine shown in the prior figures.

Fig. 11 is a sectional view taken on the line 11—11 of Fig. 10.

Fig. 12 is a perspective view of the strip used for covering one section of the handbag frame.

Fig. 13 is an enlarged fragmentary detail view of a portion of Fig. 7.

The handbag frame covering machine, according to this invention, includes a stationary U-shaped frame consisting of side arms 10a and 10b and a bottom arm 10c. This stationary frame is mounted upon a table 11. A pair of spaced guide elements 12 (see Figs. 1 and 6) are mounted upon the inner faces of the side arms

and the bottom of the U-shaped frame. These spaced guides serve to form a groove 13 therebetween into which one section of the handbag frame may be engaged.

More particularly, the handbag frame is shown in Fig. 10 to comprise a section 14 pivotally connected at its ends to the ends of a section 14'. Each of the sections 14 and 14' is constructed of U-shaped channel material, as is clearly shown in Fig. 10. The frame sections 14 and 14' are shown equipped with latch pieces 15 and 15' adapted to interengage when the frame sections are closed to hold the handbag closed. The machine, according to this invention, is capable of covering the frame sections 14 and 14' with a strip of material 16. This strip of material is formed with an opening 17 through which the latch elements 15 or 15' may extend. Preferably, the strip of material 16 should be coated with rubber cement or similar material which is capable of becoming soft when heated so as to insure the maintenance of its position on the frame when once engaged. In order to soften the material on the strip 16 there is an electric heater 18 attached upon the bottom of the U-shaped frame, on the portion 10c.

Means are provided for releasably holding the strip of covering material 16 across the top of said U-shaped frame so that one of the U-shaped sections 14 or 14' of the handbag may be manually pressed downwards on said strip and be forced in between said spaced guides 12 so that the covering material extends across the back and along the sides of the frame section.

In Fig. 6 the dot and dash lines show the handbag frame in position. It should be noted that one section of the handbag frame is engaged into the grooves 13 on the inner sides of the U-shaped stationary frame 10a, 10b and 10c. The other section of the handbag frame extends upwards out from the stationary U-shaped frame, and is idle.

The releasable means referred to in one of the previous paragraphs comprises a pair of horizontal support plates 20a and 20b supported on opposite ends of the U-shaped stationary frame. These support plates are secured on brackets 21 attached upon the table. A releasable latch is associated with each of the plates 20a and 20b, and each latch comprises a pair of arms 22a and 22b pivotally mounted at their rear ends 23 upon the plate and urged together by a spring 24. Each spring is located beneath the top portion of the bracket 21 and has its ends extending up through slots 25 in the plate and connects with

the arms. Handles 26 are hingedly mounted at their inner ends through the plates 20 or 20b, as the case may be, by hinges 21'. Each handle 26 extends outwards and upwards at an inclination, as clearly shown in Fig. 2, and has a depending cam 27. Each cam is of wedge shape and engages in between the arms 22a and 22b. The construction is such that the outer end of each handle 26 may be pressed downwards to cause the arms 22a and 22b to separate. Then the strip 16 may be laid across between the plates 20a and 20b. The ends of the strips may be releasably held by releasing the handles 26 so that the arms 22a and 22b engage thereover. In Fig. 1 the full lines 15 show the arms in the closed position, while the dot and dash lines show the arms open. Several pins 28 project from opposed segmental plates 30a and 30b arranged at the sides of the U-shaped stationary frame, as hereinafter further described, and serve to assist in holding the strip 16 in an initial horizontal position.

Corner dogs 31 are slidably arranged in the corners of the stationary frame within the groove 13 and are adapted to be moved against the corners of the handbag frame section to hold the strip 16 tightly against the corners during the application of the strip. These dogs 31 are associated with mechanism by which they may be forced into operative positions, as stated. This mechanism consists of a rigid tail 32 projecting from the rear end of each dog and connected with a plate 33 which is pivoted thereon and normally urged into an aligned position by a flat spring 34. Each flat spring is secured at one end upon a tail 32 and at the other end engages the plate 33. Each plate 33 is pivoted at the point 33'. It is adapted to swing to an open position as shown in Fig. 8, or to a closed position as shown in Fig. 7. In the closed position the plate 33 is 40 in line with the portion 32.

A headed stud or screw 35 is mounted on one side of each of the portions 32 and is engaged by one end of a bell crank 36. Each bell crank is pivotally mounted at the point 37 intermediate 45 of its ends on a bracket 38 attached upon the bottom of the table 11. The upper end of each bell crank 36 is formed with a bayonet slot 39. This bayonet slot 39 is substantially of L-shape and communicates with the side of the arm of the bell crank 36. In the normal position of each dog 31, that is, its lowered position the screw 35 is disposed within the inner end of the bayonet slot 39 as clearly shown in Fig. 5. If the bell crank is moved clockwise the dog 31 will be 50 forced inwards because of the shoulder 39' and the bayonet slot 39 engaging against the screw 35. It is only through a limited distance that the dog will be moved since the bell crank is pivoting about the point 37', while the dog 31 is 55 moving at an oblique angle to the arm of the bell crank. A certain point will be reached when the slot 39 will allow the screw 35 to pass out through the open end of the bayonet slot. A spring 40 is 60 connected with each plate 33 and with a fixed post 41 supported on the table 11 so as to normally urge the dog into its outer position. Each spring 40 also supplements the action of the spring 34 in keeping the portion 33 in line with the tail 32. Each bell crank 36 is urged into the 65 position shown in Fig. 5 by a spring 42 acting between the bell crank and the table 11. A connecting rod 43 connects with the outer end of each bell crank.

70 A horizontal link 44 connects between the outer

ends of the connecting rods 43. This link 44 is engaged by a resilient element such as a helical spring 45 which is mounted on a rod 46 passing through an aperture in the connecting bar 44. The spring 45 acts against the top of the bar 44 5 and a washer 47 held in fixed position by a nut 48 on the rod 46. The rod 46 extends downwards and is adapted to be moved downwards by some means not shown on the drawings, during the operation of the machine. As a suggestion, 10 this downward moving device may be conventional pivoted foot pedal.

A transverse stop pin 50 projects from each tail 32 and is adapted to strike an edge of the stationary U-shaped frame as shown in Fig. 7 so 15 as to prevent the dog 31 from moving too far inwards and crushing and ruining the U-shaped handbag frame.

The plates 30a and 30b are sectional plates, each composed of three sections as clearly shown, 20 for example, in Fig. 5. There is a central section which appears in Fig. 5 as of inverted funnel form. Then there are end sections in edge contact with the side of the central section. These sectional plates are movably supported on car- 25 riages 51 slidably mounted on the table 11. The carriages 51 have base portions 51a resting upon the table 11 and vertical portions 51b. It is upon these vertical portions that the sectional plates are mounted. The sectional plates 30a and 30b 30 also have corresponding sections on opposite sides of each of the vertical portions 51b of the carriages. This is clearly shown in Fig. 6. The front and rear sectional plates are connected with each other by bolts 52 so that they move in uni- 35 son. They are normally urged into retracted positions by springs 53 which act between the bolts 52 and a bolt 54 mounted upon the portion 51b and extending through a slot 55 in the central sections of the plate. The end sections of 40 the plate are connected with each other by bolts 56 extending through inclined slots 57 and the vertical portions 51b of the carriage.

Each of the carriages 51 is connected with a mechanism by which they may be moved into 45 operative positions in which the sectional plates are aligned with the groove 13 of the U-shaped stationary frame, or in inoperative positions, as for example shown in Fig. 3, where they are materially spaced apart. These carriages 51 are 50 moved by bell cranks 60 which are pivotally mounted at their centers by the pins 61 upon frames 62 attached on the table 11. These bell cranks extend through openings 63 in the table top 11. The carriages 51 are limited in motion 55 by studs 64 connected with the ends thereof and passing through studs 65 mounted on the table top. Adjustment nuts 66 are threadedly engaged on the studs 64 by which the amplitude of motion of the carriages may be limited. The bell 60 cranks 60 are normally urged into inoperative positions by springs 67 which act between the bell cranks and the table top. These springs urge the carriages into their extended positions. Links 68 connect with the inner ends of the bell 65 cranks 60 and with a connecting bar 69 through which the rod 46 also passes. A nut 70 is mounted upon the rod 46 and is adapted to engage the bar 69 to move the bar downwards to pivot the bell cranks and move the carriages 51 together. 70

An apparatus is provided for moving the parts of the segmental plates into the channel formation of the bag frame to bend in the edges of the strip of material into the channel formation, and thereafter withdrawing said segmental plates. 75

This means consists of a frame composed of spaced frame sections 75a and 75b, each engaged respectively across the tops of the segmental plates. These frame sections 75a and 75b are mounted upon the carriages 51 so as to be in operative positions at all times. The frame sections 75a and 75b are connected with each other for unitary motion by a plate 76. This plate connects with a rod 77 extending downwards and intended to be connected with some depressing device, as for example, a standard foot pedal, not shown on the drawings.

On each of the frame sections 75a and 75b there is a horizontal channel shaped member 78 resiliently supported by studs 79 thereof passing through the tops of the frame sections. Springs 80 are arranged on these studs 79 to resiliently urge the channel members 78 downwards. Three rollers 81a, 81b and 81c are mounted in each of the channel members 78 and are adapted to selectively engage the three top edges of the sections of the segmental plates. The channel shaped members 78 of the frames 75a and 75b are in different elevations, as clearly shown in Fig. 6, so that the segmental plates 30a and 30b will be operated in succession; first one, then the other.

The carriages 51 are slidably mounted on the table 11 by stationary tracks 85 (see Fig. 1). In Fig. 2 the three springs 53 which act between the studs 52 and the screw 54 for urging the three sections of each segmental plate into the retracted position, are clearly shown.

The operation of the device is as follows:—A strip of material 16 which is preferably, but not necessarily, coated with rubber cement, is placed across the plates 20a and 20b and releasably held by the fingers 22. These fingers may be momentarily spread by depressing the handles 26 so that the cams 27 engage the adjacent sides of the fingers 22. A handbag frame section such as the frame section 14 or 14' is then placed upon the strip 16 so that the latch portion 15 or 15' thereof passes through the opening 17 of the strip. The frame section is moved downwards, the fingers 20 releasing the strip during this downward motion. The handbag frame section is moved completely downwards within the groove 13 between the guides 12 of the stationary U-shaped frame 10a, 10b and 10c.

The rod 46 is then moved downwards and the spring 45 upon the rod will immediately move the transverse bar 44 along. The motion from this bar is transmitted by the links 43 to the bell cranks 36 which move the dogs 31 inwards. The strip 16 is thus tightly pressed against the corners of the handbag frame by the dogs. The pins 50 prevent the dogs from moving too far and damaging the handbag frame. Slightly prior to this moment, the nut 70 engaged the bar 69 and moved the links 68 downwards and caused the carriages 51 to move together. The segmental plates 30a and 30b will thus engage against the sides of the strip 16 and hold them in the positions shown by the dot and dash lines in Fig. 11. When the plates have reached this position and the sides of the strip of material 16 are now held, the screws 35 will reach the open ends of the bayonet slots 39 and the spring 40 will immediately retract the dogs 31.

The operator of the machine then moves the rod 11. This moves down the plate 76 which is connected therewith, and moves down both of the frames 75a and 75b. The rollers 81a, 81b, and 81c of the lowermost channel member 78 strike the top edges of the three sectional plates of the seg-

mental plate 30b which immediately forces the central plate downwards and the side plates outwards and so bends one side of the strip 16 into the hollow of the channel of the U-shaped handbag frame. Further depression of the rod 11 causes the rollers of the other channel shaped member 78 to engage against the top edges of the segmental plate 30a and eventually force the central segment downwards and the side segments outwards to bend in the other side of the strip 16. The handbag frame is now fully covered by the strip 16.

When the rod 11 is released it will be moved upwards and first the sectional plate 30a will be withdrawn from its operative position, then the sectional plate 30b will be withdrawn. Upward motion of the rod 46 will move the carriages 51 into their inoperative positions and will permit the transverse bar 44 to move upwards. As the bar 44 moves upwards the bell cranks 36 will pivot anti-clockwise and cam corners 39a of the open ends of the bayonet slots 39 will engage against the screws 35 and flex the portions 33 to the position shown in Fig. 8, and then permit the screws 35 to engage into the bayonet slots. When the screws engage in the slots the plates 33 will snap back to their aligned position. The device is then in its original condition and ready to repeat its operation.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A handbag frame covering machine, comprising a U-shaped stationary frame having spaced guides along the inner faces of the side arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidably in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, means for moving the parts of said segmental plates into said channel formation to bend in the edges of the strip of material and then withdrawing said segmental plates.

2. A handbag frame covering machine, comprising a U-shaped stationary frame having spaced guides along the inner faces of the side arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidable

in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, means for moving the parts 5 of said segmental plates into said channel formation to bend in the edges of the strip of material and then withdrawing said segmental plates, and means for retracting the corner dogs prior to moving the segmental plates to align the edges of 10 the strip of material with the hollow of said channel.

3. A handbag frame covering machine, comprising a U-shaped stationary frame having spaced guides along the inner faces of the side 20 arms and the bottom, means for releasably holding a strip of covering material across the top of said U-shaped frame so that a U-shaped channel material handbag frame may be manually pressed downwards on said strip and forced in between 25 said spaced guides so that said covering material extends across the back and along the sides of said channel formation, corner dogs slidable in the corners of said stationary frame, means for forcing said corner dogs against the corners of said 30 U-shaped bag frame, a carriage movably mounted to each side of said U-shaped stationary frame, opposed segmental plates movably supported on said carriages, means for moving the carriages towards each other to align the edges of the strip 35 of material with the hollow of said channel formation, means for moving the parts of said segmental plates into said channel formation to bend in the edges of the strip of material and then withdrawing said segmental plates, said 40 stationary frame being mounted upon a table.

4. A handbag frame covering machine, comprising a U-shaped stationary frame having spaced guides along the inner faces of the side arms and the bottom, means for releasably holding a strip of covering material across the top of 45 said U-shaped frame so that a U-shaped channel material handbag frame may be manually pressed downwards on said strip and forced in between said spaced guides so that said covering material extends across the back and along the sides of 50 said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the 55 carriages towards each other to align the edges of the strip of material with the hollow of said channel formation, means for moving the parts of said segmental plates into said channel formation to bend in the edges of the strip of material and then withdrawing said segmental plates, and means for retracting the corner dogs 60 prior to moving the segmental plates to align the edges of the strip of material with the hollow of said channel, said means for releasably holding the strip of covering material comprising horizontal plates stationarily supported and fingers 65 adapted to engage over the edges of said strip of material.

5. A handbag frame covering machine, comprising a U-shaped stationary frame having spaced guides along the inner faces of the side 70 arms and the bottom, means for releasably hold-

ing a strip of covering material across the top of said U-shaped frame so that a U-shaped channel material handbag frame may be manually pressed downwards on said strip and forced in between 5 said spaced guides so that said covering material extends across the back and along the sides of said channel formation, corner dogs slidable in the corners of said stationary frame, means for forcing said corner dogs against the corners of said U-shaped bag frame, a carriage movably 10 mounted to each side of said U-shaped stationary frame, opposed segmental plates movably supported on said carriages, means for moving the carriages towards each other to align the edges of the strip of material with the hollow of said 15 channel formation, means for moving the parts of said segmental plates into said channel formation to bend in the edges of the strip of material and then withdrawing said segmental plates, and means for retracting the corner dogs prior to 20 moving the segmental plates to align the edges of the strip of material with the hollow of said channel, said means for forcing said corner dogs against the corners of said U-shaped bottom plate, comprising tail portions mounted upon the 25 corner dogs and associated with resilient portions adapted to assume aligned positions or resiliently bent therefrom, bell cranks with bayonet slots engaging headed screws mounted upon the resilient moveable portions of the tail pieces, links 30 and bars connected with the bell cranks, and a depressible rod by which the bell cranks may be pivoted to move the dogs forward.

6. A handbag frame covering machine, comprising a U-shaped stationary frame having spaced guides along the inner faces of the side arms and the bottom, means for releasably holding a strip of covering material across the top of 35 said U-shaped frame so that a U-shaped channel material handbag frame may be manually pressed downwards on said strip and forced in between said spaced guides so that said covering material extends across the back and along the sides of 40 said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the 45 carriages towards each other to align the edges of the strip of material with the hollow of said channel formation, means for moving the parts of said segmental plates into said channel formation to bend in the edges of the strip of material and then withdrawing said segmental plates, and means for retracting the corner dogs prior to 50 moving the segmental plates to align the edges of the strip of material with the hollow of said channel, said means for forcing said corner dogs against the corners of said U-shaped bottom plate, comprising tail portions mounted upon the 55 corner dogs and associated with resilient portions adapted to assume aligned positions or resiliently bent therefrom, bell cranks with bayonet slots 60 engaging headed screws mounted upon the resilient moveable portions of the tail pieces, links and bars connected with the bell cranks, and a depressible rod by which the bell cranks may be pivoted to move the dogs forwards, said bayonet 65 slots being adapted to release the dogs and so allow the dogs to seek withdrawn positions.

7. A handbag frame covering machine, comprising a U-shaped stationary frame having spaced guides along the inner faces of the side 70

arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, means for moving the parts of said segmental plates into said channel formation to bend in the edges of the strip of material and then withdrawing said segmental plates, and means for retracting the corner dogs prior to moving the segmental plates to align the edges of the strip of material with the hollow of said channel, comprising bell cranks with bayonet slots engaging headed screws on resiliently mounted portions of tail pieces connected with said dogs, resilient means connected with the said resilient tail pieces substantially as described.

30 8. A handbag frame covering machine, comprising a U-shaped stationary frame having spaced guides along the inner faces of the side arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, and means for moving the parts of said segmental plates into said channel formation to bend in the edges of the strip of material and then withdrawing said segmental plates, said means for moving the segmental plates being adapted to move the plates selectively, and then withdrawing the plates selectively.

35 50 55

9. A handbag frame covering machine, comprising a U-shaped stationary frame having spaced guides along the inner faces of the side arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, and means for moving the parts of said segmental plates into said channel formation to bend in the edges of the strip of material and then withdrawing said segmental plates, said means for moving the segmental plates being adapted to move the plates selectively, and then withdrawing the plates selectively.

10. A handbag frame covering machine, comprising a U-shaped stationary frame having spaced guides along the inner faces of the side arms and the bottom, means for releasably holding a strip of covering material across the top of said U-shaped frame so that a U-shaped channel material handbag frame may be manually pressed downwards on said strip and forced in between said spaced guides so that said covering material extends across the back and along the sides of said channel formation, corner dogs slidable in the corners of said stationary frame, means for forcing said corner dogs against the corners of said U-shaped bag frame, a carriage movably mounted to each side of said U-shaped stationary frame, opposed segmental plates movably supported on said carriages, means for moving the carriages towards each other to align the edges of the strip of material with the hollow of said channel formation, and means for moving the parts of said segmental plates into said channel formation to bend in the edges of the strip of material and then withdrawing said segmental plates, said means for moving the segmental plates being adapted to move the plates selectively, and then withdrawing the plates selectively.
